OSCILLATION GENERATION

Walter van B. Roberts, Princeton, N. J., assignor
to Radio Corporation of America, a corporation
of Delaware

Application January 7, 1939, Serial No. 249,750

2 Claims. (Cl. 250—36)

The present invention relates to an oscillator circuit of the type employing degeneration to improve its stability.

The primary object of the invention is to simplify the stabilization of oscillation generator systems. In one embodiment of the invention the frequency of oscillation is stabilized, while in another embodiment both frequency and amplitude of oscillation are stabilized.

A better understanding of the invention may be had by referring to the following description, which is accompanied by a drawing wherein Figs. 1 and 2 show, by way of example only, two oscillation generation systems of the present invention, differing from one another only in the type of resistance used in the cathode lead.

Referring to the drawing, wherein like parts are represented by like reference characters, there is shown in each of Figs. 1 and 2 an oscillation generation system comprising an evacuated electron discharge device having a control grid G, a cathode K, a screen grid SG, and a plate P. Although a screen grid tube has been shown in the drawing, it should be understood that this is merely illustrative of any type of vacuum tube having a plurality of electrodes, the invention not being limited to a tetrode. In circuit with the cathode K between two points thereof, there is a pure resistive impedance R or R'. In circuit with the grid G and plate P, there are, respectively, inductance coils L_g and L_p, both of which are coupled to the coil L_o of a parallel tuned oscillatory circuit O. Coils L_g and L_p may be made of fine resistance wire, or have resistors connected in series with them in known fashion to prevent parasitic oscillation. It should be noted that connections extend from the grid circuit, plate circuit, screen grid circuit, and cathode circuit to a point of common radio frequency potential, such as ground. Fig. 2 differs from Fig. 1 only in the type of resistive impedance used in the cathode circuit, the resistor R' being shown as an electrical light bulb whose alternating current resistance increases with increase in temperature.

An exposition of the theory and the operation of the invention follows: The pure resistive impedance R or R', or putting it another way, the unbypassed resistor, inserted between two points in the cathode lead of the vacuum tube, results in the plate current i_p in the tube being given by the expression

$$\frac{g_m e_g}{1 + g_m R}$$

where g_m=the transconductance of the tube and e_g=the voltage induced in the grid circuit. The condition for oscillation of this circuit may be derived as follows: e_g=jωM₁i, where i is the current in coil L_g.

The voltage induced in the tank circuit

$$O=j\omega M_2 i_p$$

10 while the voltage drop in the tank circuit O=i_r, where M₁ is the mutual inductance between the grid coil L_g and the coil L_o of the oscillatory circuit O, and M₂ is the mutual inductance between the plate coil L_p and the coil L_o of the oscillatory circuit O.

For sustained oscillation, these two voltages must add to zero. Replacing i_p by its expression in terms of g_m, R, ω, M₁ and i, this condition becomes

$$\frac{\omega^2 M_1 M_2}{r} = R + \frac{1}{g_m}$$

If the left side of this equation is larger, the amplitude of oscillation will increase with time.

It will thus be seen that if R is large compared to

$$\frac{1}{g_m}$$

(or in other words, if Rg_m is large compared to unity) the condition of oscillation is dependent only to a slight degree upon the value of g_m. The circuit is thus stabilized against the effect of variation of electrode voltages, change of tubes, or any other factors which affect the value of g_m.

As with any ordinary oscillator circuit however, when the condition for starting of oscillations is met, these oscillations will build up in amplitude until grid current flows with a resulting increase in the effective value of the circuit resistance r, or else the tube operates over such a wide range of its characteristic that the effective g_m of the tube decreases. For either or both of these reasons, the amplitude comes to a limiting value. In order, however, to limit the amplitude to a value less than that which introduces the additional losses or the non-linear action mentioned above, the degenerative resistance R may be of the type whose alternating current resistance increases with increase in temperature, as indicated by the electric light bulb R' of Fig. 2, so that as the amplitude of oscillations increases, its alternating current resistance value increases so that the amplitude of oscillations is maintained without further increase at a small value

which does not introduce losses in the circuit or distortion in the tube. The introduction of such a resistance in other circuit arrangements for vastly different purposes is known and need not be further described.

While an electric light bulb has been mentioned and illustrated in Fig. 2, any other type of resistor may be used whose resistance increases with increase in oscillation amplitude.

While I have shown and described two specific forms of the invention, it will be understood that many modifications thereof will be readily apparent to one skilled in the art without losing the benefits of simplicity provided by the present invention. The essential conditions to be met are that plate circuit should be coupled to the oscillatory circuit and the oscillatory circuit in turn so coupled to the grid circuit as to produce a relatively large regenerative grid voltage which is in phase with the plate current at the resonant frequency, but out of phase therewith except at resonance, while at the same time the plate current produces a slightly smaller degenerative grid voltage which is independent of frequency.

What is claimed is:

1. In combination, in an oscillation generation system, an evacuated electron discharge device

having control grid, cathode and plate electrodes, individual connections each including an inductance coil from said control grid and plate electrodes to a reference point, a parallel tuned oscillatory circuit having an inductance coil coupled to said coils in said grid and plate connections, and a resistor having negligible shunt capacity connected between said cathode and said reference point, said resistor having a value as large as possible but which will not stop oscillations and being of such type that its resistance increases with increase in current flow therethrough.

2. In combination, in an oscillation generation system, an evacuated electron discharge device having control grid, cathode and plate electrodes, individual connections each including an inductance coil from said control grid and plate electrodes to a reference point, a parallel tuned oscillatory circuit having an inductance coil coupled to said coils in said grid and plate connections, and a resistor having negligible shunt capacity connected between said cathode and said reference point, the resistor being such that its value increases with current flow therethrough.
